[57] CLAIM

The ornamental design for a combined vehicle steering wheel and keyboard housing, as shown and described.

DESCRIPTION

FIG. 1 is a perspective view of a combined vehicle steering wheel and keyboard housing showing my new design;

FIG. 2 is a front elevational view thereof;

FIG. 3 is a bottom plan view thereof;

FIG. 4 is a side elevational view thereof.

A portion of the rim of the steering wheel has been broken away and one of the spokes shown in section in FIGS. 3 and 4 for clarity of illustration.
